UNITED STATES PATENT OFFICE.

FRANCIS L. ELLINGWOOD, OF NEW YORK, N. Y.

CONSTRUCTION OF FLOORS, &c.

SPECIFICATION forming part of Letters Patent No. 712,278, dated October 28, 1902.

Application filed June 25, 1902. Serial No. 113,103. (No model.)

To all whom it may concern:

Be it known that I, FRANCIS L. ELLINGWOOD, a citizen of the United States of America, and a resident of New York, county of New York, and State of New York, have invented certain new and useful Improvements in the Construction of Floors and other Parts of Buildings and other Structures, of which the following is a specification.

10 My invention relates to an improvement in the construction of floors, roofs, partitions, decks, or other parts of buildings and similar structures, the object being to provide a form of construction for these parts which will be 15 fireproof or will serve as a fire-retardant, will be dust-proof, air-proof, and waterproof, will be economical, saving in space, and sufficiently stiff and unyielding to prevent warping and lessen shrinkage, as well as to attain 20 numerous other incidental advantages arising from the combination of a metallic surface with a surface of wood or other fibrous or composition material.

The invention consists, essentially, in the 25 combination of a plate or sheet of metal having ribs, seams, or corrugations with a floor or other similar surface of wood or fibrous or other material, together with means for uniting the two things in order that a stiff metal-lined floor or other surface-covering may be 30 the result of such union; and the invention also consists in numerous details in the construction, combination, and arrangement of the various parts, substantially as will be 35 hereinafter more fully described and claimed.

In the accompanying drawings, illustrating 40 my invention, Figure 1 is a perspective view of a section of flooring or other structure made in accordance with my present improvements. Fig. 2 is a detail edge view of a part of one 45 of the floor-boards with the ribbed plate arranged therewith and shown in section. Fig. 3 is a transverse section of the floor-piece with the plate-rib that engages the kerf there- 50 in shown in side view. Fig. 4 represents a view of a floor-piece and ribbed plate engag- 55 ing it, together with a section of one form of tool employed for cutting and bending sec- 60 tions of the plate-ribs to cause a tight con- 65 nection to be made between said ribs and the 70 floor-pieces. Fig. 5 is a similar view and shows the position of the tool at the comple- 75

tion of the cutting operation, whereas in Fig. 4 the tool is indicated in the position it occupies immediately prior to the commencement 55 of the cutting operation. Fig. 6 is a perspective view of the operative end of the tool.

Similar numerals of reference designate corresponding parts throughout the different figures of the drawings.

1 denotes a floor board or piece of any suitable, well-known, and ordinary form and having along one longitudinal edge a tongue 3 and along the other longitudinal edge a groove 2, the tongue of one board being adapted to 65 take into the groove of the adjacent board, and thereby effect a tongue-and-groove connection between adjacent boards after the manner of the common construction of flooring, sheathing, wooden partitions, and the 70 like. The floor-piece 1 is shown here simply by way of example as one of many kinds that might be used in carrying my invention into practical effect. Said piece 1 may be a floor-board or it may have any other purpose or 75 function in the construction of buildings and other structures, and it may be of wood or any other suitable material and may vary in shape, style, and purpose within as wide limits as may be desired.

80 4 indicates a plate or sheet of metal or other suitable similar stiff material having any desired size and shape. It is provided with a series of ribs, seams, or corrugations 5, struck up therefrom or stamped or otherwise fashioned in any desired manner, said ribs being preferably parallel to each other, although I reserve the liberty of locating them in any other position relatively to each other. The plate 4 may be large or small, as preferred. 85 In the ordinary construction of a floor said plate may be of considerable size and may be united at the edges with adjacent similar plates. The ribs, seams, or corrugations may vary widely in form, being not necessarily 90 flat and thin, as indicated in the drawings; but they may have any fitting breadth or contour.

When the metal plates and the wooden pieces are joined together in the laying of a 95 floor or in the construction of a partition or wainscoting or other part of a building, the metallic ribs 5 will be caused to enter transverse slots, cuts, or saw-kerfs 6, made in the

wooden piece 1; or, to state it in another way, the metallic plates having first been rigidly supported on the beams or other parts of the building construction and the floor-pieces 1 5 having been provided with the transverse cuts 6, substantially equal in size to the ribs 5 and extending only part way through the width of piece 1, the pieces can then be fitted down over the ribs 5, the tongues 3 being at 10 the same time carried into engagement with the grooves 2 in the ordinary manner. After the floor-pieces have thus been laid upon the ribbed metallic plates the next thing necessary is to firmly unite the two, and this I accomplish 15 without the use of nails or screws or other similar devices by merely bending down on or in the boards a short segment of each rib at the point where it passes through the longitudinal groove 2 or causing lugs or 20 projections to be formed on the ribs that will have a locking effect on the surface covering. In Figs. 3 the rib 5 is shown in section projecting partially across the groove 2, and in Fig. 2 it is shown in the saw-kerf 6 and also in 25 the place where it crosses the groove 2, but before its cut-out part has been clenched in said groove. Now in order to turn down the edge or a portion of the edge of the rib laterally within groove 2 and seat it with a clenching or 30 gripping effect upon the side of said groove 2, I preferably employ some sort of a tool, an example of which is indicated at 8 in Figs. 4, 5, and 6. Tool 8 is adapted to be acted upon by a mallet or hammer, and the impact of the blow 35 upon the head of the tool is intended to make the proper cuts and the lateral transverse overturn of a section of the rib. The operative end of the tool 8 accordingly has two cutting edges, one being an outer lip 10 and the other the inner cutting edge 11, the connection between the two cutting edges 10 and 11 being preferably curved, as shown. Adjacent to the inner cutting edge 11 is a slot 13, between two flanges or guides 9, 9, said slot 13 being adapted to receive 40 the rib 5 therein when the tool is in working position, whereby the tool is controlled, directed, and guided in doing its work. In Fig. 4 the tool is shown when ready to be struck by the mallet, and it will be noted 45 that here it is in an inclined position and that the cutting edges 10 and 11 both rest on the edge of the rib 5, while the guides 9, 9 embrace the rib while the latter is in the slot 13. The effect now of giving quite a hard blow 50 upon the head of the tool 8 will be to cause the cutting edges 10 and 11 to cut a certain distance into the ribs 5 on inclined lines, as shown in Fig. 5, and simultaneously with this cutting to lay over the section 7, which is between 55 the cuts in the rib laterally upon the proximate surface of groove 2, as shown in Figs. 1 and 5, tightly binding this section 7 upon the wood, and in fact driving it down, or so firmly seating it horizontally therein 60 that it will afford no appreciable obstruction to the entrance into groove 2 of the tongue 3 of the next floor-board to be laid. One effect

of the action of cutting edge 10 is to leave a sharp projection 12 within the groove 2. This projection will enter the tongue 3 of the next floor-board when the latter is laid in place, and thus assist in making a tighter joinder of the boards; but it will be understood that the tool 8 is simply a specimen tool for the purpose. Other tools of various forms 75 may be utilized, if preferred. Of course with different tools the cut in the rib and the manner of bending over the cut-out section will be changed and varied.

I desire to claim, broadly, the feature of the 80 bent projections on the ribs, whatever may be the size, form, or shape of said projections, however they may be made, the functions of the projections being to engage and tightly connect the surface covering with the ribbed 85 plate. As the tools for making them may vary widely so the projections may have a great diversity, and they may either be formed at the time the ribs are first shaped or afterward. Also the surface covering may vary 90 widely, as above indicated. I am not confined to wooden or other boards or pieces; but the invention is broad enough to embrace compositions of material that may be placed in a plastic form on the ribbed plate, its ribs 95 having been previously cut or notched to provide the locking projections, which composition is allowed to harden, and thus a surface composition covering be firmly united to the plate. 100

Many changes besides what I have spoken of in the embodiment of this invention may be made without departing from the scope and intent thereof, and I reserve the liberty of varying the same in many ways, adapting 105 it for use in any location where it will serve the purpose and rearranging and changing the precise details to suit the exigencies of different cases.

Having thus described my invention, what 110 I claim as new, and desire to secure by Letters Patent, is—

1. In the construction of floors and other parts of buildings and other structures, the combination with a ribbed plate, of a surface 115 covering, and means on the ribs of the plate for firmly uniting said covering thereto.

2. In the construction of floors and other parts of buildings and other structures, the combination with a rib-provided plate, of a 120 surface covering transversely grooved to receive the ribs, and means consisting of laterally-bent portions of the ribs for firmly uniting the said covering to the plate.

3. In the construction of floors and the like 125 for buildings and other structures, the combination with a rib-provided plate, of strips of flooring tongue-and-grooved together and provided with transverse cuts to receive the said ribs, and means consisting of laterally-bent portions of the ribs which are seated firmly within the grooves of the flooring-strips 130 for uniting the latter to the plate.

4. In the construction of floors and the like

for buildings and other structures, the combination with a plate provided with ribs having portions thereof cut out and laterally bent to engage the floor-boards, of said floor-
5 boards tongue-and-grooved together and provided with transverse cuts to receive the ribs, substantially as described.

5. The combination with a plate having parallel ribs, seams or corrugations, of a surface
10 covering having cross-cut grooves engaging the ribs, said ribs having sections cut and bent laterally to a seat within grooves of the surface covering.

6. The combination with a plate having parallel ribs, of boards or strips having transverse grooves to receive the ribs, said ribs having inclined cuts therein to provide a turned-down section for gripping and clenching the
15

pieces in order to make a tight union between the latter and the plate.

7. The combination with a plate having ribs, sections of which are cut out and laterally turned, of a covering for said plate composed of a plurality of strips transversely grooved to receive the ribs, said strips being engaged by the laterally-turned sections of the ribs.

8. The combination with a plate having ribs provided with projections thereon, of a surface covering that is firmly united to the plate by means of said projections.

Signed at New York this 19th day of June, 1902.

FRANCIS L. ELLINGWOOD.
